UNITED STATES PATENT OFFICE.

KENJI HORIHATA, OF NEW YORK, N. Y.

WINDOW CLEANER.

Application filed February 16, 1927. Serial No. 168,732.

My invention relates to a window cleaner and more particularly is intended as an improvement on the window cleaner forming the subject of my United States patent application filed August 18th, 1926, Serial No. 130,021.

The general object of my present invention is to variously improve the window cleaner referred to with respect to the arrangement of the cleaning and drying parts and their holding means, and to otherwise simplify and provide an efficient structure of window cleaner.

The nature of my present invention and its distinguishing features and advantages will clearly appear as the description proceeds.

Reference is to be had to the accompanying drawings forming a part of this specification, it being understood that the drawings are merely illustrative of one example of the invention.

Figure 1 is a perspective view of a window cleaner embodying my present invention, showing the same in position for use on a window pane, shown in part.

Figure 2 is an enlarged vertical section through the cleaning heads and adjacent parts of the handles.

Figure 3 is an elevation of one of the cleaning heads with the pads and back plate removed, the view being given to show more clearly the springs that control the clamps for holding the pads in place.

Figure 4 is an edge view of one of the pads.

Figure 5 is a detail in transverse section, as indicated by the line 5—5 in Figure 4.

In carrying out my invention in accordance with the illustrated example two handle members 10 are provided joined by a cross bar 11 adapted to be grasped by the user of the device. Two cleaning heads are provided designated generally by the numeral 12. Bails 14, 114 are pivotally secured to the respective heads 12, said bails having pins 13, 113 secured to the respective handles 10, the pins 13 being inserted directly in the end of one handle member 10, and the other pins 113 being inserted in rolled edges 115 of a semi-cylindrical element 15 on the other handle member 10.

The handle sections 10 are made in telescopic sections, the upper section having a groove 16 and the lower section having fixed thereto at the interior of its tubular end a block 17 slideable in the groove 16, said block being held by suitable fasteners 18. A set screw 19 is provided extending through the tubular telescoping section and through the block 17 to bind against the bottom of the groove 16 for holding the telescoping sections in adjusted position. (See Figure 2.)

Each head 12 has a plurality of layers 20 of fabric at one side for washing the window and a plurality of suitable layers 21 at the opposite side for drying. In the medial plane of each head is a plate 22, the ends of which have curved flanges 23. Clamp plates 24 are provided to clamp the edges of the fabric layers 20 and 21, the ends of which fabric layers are turned over the flanges 23. A clamp 24 is provided on the top and bottom of each head 12 to hold the fabric 20 and 21. Springs 25, shown best in Figure 3, resiliently press the clamp plates 24 against the fabric layers.

At one side of each flange 23 a waterproof and non-absorbent strip of fabric 29 is provided over the turned-over edges of the washing fabric layers 20, to prevent the water from passing to the drying fabric layers 21.

Backing plates 26 are provided at the interior of each head 12 against which the fabric layers 20 and 21 are held. On each backing plate 26 is a side flange 27 having tongues 28 bent over the side edges of the fabric layers 20. A pad 120 may be provided between backing plate 26 and the fabric 20 and a similar pad 121 provided between the fabric layers 21 and adjacent backing plate 26.

The semi-cylindrical element 15 is disclosed fully in my aforementioned application, wherein it is explained that said element is pivoted on its lower end and held by a latch 30, said pivoted element and the latch referred to not forming part of the present invention.

I would state furthermore, that while the illustrated example constitutes a practical embodiment of my invention, I do not limit myself strictly to the exact details herein il-

lustrated, since, manifestly, the same can be considerably varied without departure from the spirit of the invention as defined in the appended claim.

5 What I claim is:

In a window cleaner a cleaning head comprising a central plate having curved flanges on each side of said plate at the top and

bottom, clamp plates for said flanges, a fabric sheet having its edge portions disposed between said flanges and said clamp plates and held in clamped position by said plates, and springs disposed adjacent to said flanged plate and connected to said clamp plates.

KENJI HORIHATA.
